UNITED STATES PATENT OFFICE.

HERMANN F. REINER, OF BLAIRSVILLE, ASSIGNOR TO HIMSELF AND
FRANK LOFINK, OF PITTSBURG, PENNSYLVANIA.

IMPROVEMENT IN BOTTLE-STOPPERS.

Specification forming part of Letters Patent No. 136,095, dated February 18, 1873.

To all whom it may concern:

Be it known that I, HERMANN F. REINER, of Blairsville, in the county of Indiana and State of Pennsylvania, have invented a new and useful Improvement in Bottle-Stoppers, of which the following is a specification:

This invention has for its object to furnish a stopper for bottles which shall be so constructed that the influx or efflux of liquids is rendered possible without the removal of the stopper from the bottle. The invention consists in the employment of a stopper composed of a metallic tapering tube, which is provided with a horizontal central flange and with a bayonet-slot for receiving and securing the vertical stem of a conical disk-valve, by the movement of which stem the valve is opened or closed, to admit of the induction and discharge of liquids.

In the drawing, Figure 1 is a side view of a bottle and stopper; Fig. 2, a sectional view of the stopper.

A represents the upper or neck portion of an ordinary bottle with my improved stopper fitted in the mouth of the same. B is a tapering metallic tube, the lower portion of which enters the mouth of the bottle, a tight joint being effected by means of an India-rubber packing-ring, C, surrounding said portion. D is a horizontal central flange formed on the tube B, and resting, when the stopper is applied to a bottle, upon the lip or upper end of the same. E is a series of flexible metallic strips, applied to the flange D and projecting under the external neck of the bottle, to enable a fastening-wire, N, to be coiled around the same for securing the stopper in position. F is a valve for closing and opening the lower end of the tube B, to permit of the filling of

the bottle or discharge of the contents through the same. Said valve is composed of two conical metal plates, between which is fitted and clamped an India-rubber disk, H; or the valve may be made entirely of rubber. The valve is provided with a vertical stem, I, the upper end of which is laterally extended through an elongated slot, K, formed in the tube B, the projecting portion of the stem being provided with a knob or button, L. M is a horizontal slot, arranged in relation to the vertical slot, for receiving the knob portion of the valve-stem, to secure the latter in a closed position.

From the above description it will be perceived that a bottle-stopper of the form represented by me will, in case the bottle is filled with an effervescent liquid, be an effectual medium for preventing the escape of the contents, as the internal pressure forces the valve into the mouth of the tube, thus producing a tight joint.

To discharge the contents of a bottle it is only necessary to disengage the valve-stem from the horizontal slot, when the valve automatically falls and exposes the discharge-opening, the movement of the stem and valve being limited by the vertical slot, as will be apparent.

Having thus described my invention, what I claim as new, and desire to secure by Letters Patent, is—

The bottle-stopper herein described, consisting of the tube B provided with slots K M, valve F, and bent valve-stem I, as herein shown and described.

HERMANN F. REINER.
